DRILLING MACHINE FOR DENTAL MODELS

Bernard Weissman, 236 5th Ave.,
New York, N.Y. 10001

Filed Sept. 11, 1972, Ser. No. 287,856

Term of patent 14 years

Int. Cl. D24—01

U.S. Cl. D24—1 B

FIG. 1.

FIG. 2.

FIG. 3.

FIG. 1 is a front perspective view of a drilling machine for dental models illustrating my new design, showing one side thereof;

FIG. 2 is a front perspective view showing the other side thereof; and

FIG. 3 is a rear elevational view thereof.
I claim:

The ornamental design for a drilling machine for dental models, substantially as shown.
